UNITED STATES PATENT OFFICE.

THEOPHILUS R. HYDE, JR., OF WATERBURY, CONNECTICUT, ASSIGNOR TO
THE SCOVILL MANUFACTURING COMPANY, OF SAME PLACE.

DESIGN FOR A BUTTON-FASTENING.

SPECIFICATION forming part of Design No. 32,248, dated February 20, 1900.

Application filed May 18, 1899. Serial No. 717,369. Term of patent 14 years.

To all whom it may concern:

Be it known that I, THEOPHILUS R. HYDE, Jr., a citizen of the United States, residing at Waterbury, in the county of New Haven and State of Connecticut, have invented and produced a certain new and original Design for Button-Fastenings, of which the following is a full, clear, and exact description.

- This invention relates to that class of button-fastenings which are made of metal and have prongs which protrude through the shank of the button and are engaged with the garment to secure the button to the garment in lieu of thread.
- 15 In the accompanying drawings, illustrating my invention, in the several figures of which like parts are similarly designated, Figure 1 is a top plan view of the pronged fastening. Fig. 2 is a perspective view, and Fig. 3 is a 20 longitudinal section. The drawings show the device enlarged.

As shown in the drawings, the leading or material feature of my design consists of the curved portion *a* of the head of the pronged fastening, such portion being hemispherical or 25 the segment of a hollow sphere. This curved or rounded head is surrounded by an annular plane *b*.

Having described my invention, what I claim as new, and desire to secure by Letters 30 Patent, is—

The design for a button-fastening, substantially as shown and described.

In testimony whereof I have hereunto set my hand this 17th day of May, A. D. 1899. 35

THEOPHILUS R. HYDE, JR.
